UNITED STATES PATENT OFFICE.

JESSE S. YOUNG, OF CHICAGO, ILLINOIS.

BELTING AND PROCESS OF MAKING THE SAME.

1,148,883.

Specification of Letters Patent. Patented Aug. 3, 1915.

Application filed April 13, 1914. Serial No. 831,626.

To all whom it may concern:

Be it known that I, JESSE S. YOUNG, a citizen of the United States, and a resident of Chicago, in the county of Cook and State of Illinois, have invented a certain new and Improved Belting and Process of Making the Same, of which the following is a specification.

My invention relates broadly to structures, and more specifically to composite structures formed of layers of fibrous material, such as belting, commonly used for power transmission, and has general reference, first, to the provision of an improved form of belting, and, second, to the provision of an improved process for making belting and other composite fibrous structures which are subjected to great tension in service.

The principal objects of my present invention are the provision of an improved article of the nature referred to characterized by a maximum of tensile strength and a minimum of tendency toward elongation in service; the provision in an article of the class referred to of a power transmission element wherein such tendency toward elongation has been largely removed or overcome before the article is put into service; the provision of an element of the character referred to which has been pre-stretched to a point approaching and preferably approximating its limit of elasticity, and then so treated as to set or fix it and prevent it from retracting and resuming its initial state of rest; the provision of means for preventing such resumption; the provision of means acting on the stretched element causing it, either mechanically or chemically, or both, to remain fixed or set in such elongated condition; the provision of an improved filler for this purpose; and generally to improve belting and like structures and processes of making the same, together with such further objects as may hereinafter appear.

As is well known to those who are skilled in the art, one of the greatest of desiderata is the provision of belting, either canvas, leather faced, or composite, which will not stretch in service, since such stretching involves, on the one hand either loss of power, or loss of time in making adjustments, or

on the other hand either considerable watchfulness or extensive repairs.

55

In eliminating the tendency toward stretching in service, I employ a suitable fibrous tension element, such as a canvas belt, facing it, when desired, on one or both surfaces, as conditions of service may render expedient, with a suitable traction element such as leather. The first mentioned or tension element, which for purposes of illustration may be considered as having any desired length, an initial width of 24" and a limit of elasticity not much in excess of 15% of its length, is put under tension until it is elongated about 13%, at which time it will be found decreased in width to about 23" or approximately 4%. Tension sufficient to give this amount of elongation is within my experience materially in excess of any possible strain which such tension element would meet in the practical conditions of service. While the element is still taut under tension, it is treated in such a manner as to fix or set it under such tension and prevent it from retracting and resuming its initial state when such tension is released, a preferable treatment for such purpose being the application of a fluid which will act as well chemically to fix or set the fibers in their present relation and mechanically as a filler to close the interstices between them, and, when textile fabric is employed, to fill the interstitial openings between the several warp and woof members. The fibrous element is then dried in a suitable manner, and when desired one or more suitable traction surfaces are cemented thereto.

85

In practice I find that when a filler is employed for retaining the belt in its pre-stretched condition, the prime requisite (of the filler) is that it have a good body and great permeability; a secondary factor is that it have strong sticking qualities, and desirable subsidiary features are great flexibility and quick-drying characteristics. A suitable filler composition for my present purposes is a compound of gelatin, isinglass, linseed oil, and gum mastic, proportioned according to the qualities of the articles. I do not limit myself to these particular named products, nor, the less, (since they are organic and differ at times in quality), to any

95

2
precise percentages thereof. By thus treating a canvas belt, I find, in practice, that I am able to produce a belting which for all practical purposes is stretchless, that is, 5 which will break in service before stretching materially; and furthermore one which, when faced with leather, which may be cemented thereto, is non-sagging and will at all times maintain secure engagement with 10 the leather facing, such facing having no tendency to tear away therefrom, or to crack or break as is the common experience with leather faced belts having a canvas foundation. The leather facing should preferably 15 not have all of its elasticity removed, in any event desirably not more than half thereof, before application to the canvas foundation, since a certain amount of flexibility is required by reason of the bending of the belt 20 in passing around pulleys, and it is not desirable to put the leather under tension for transmission purposes. The amount of strain above referred to elongates the fabric beyond any amount of stretch which a leather 25 facing could withstand and consequently the leather facing thereof, when such is used, would never receive in service any strain which it could not readily withstand.

In attaining the objects to which I have 30 above referred, and gaining certain additional advantages to be below pointed out, I have provided a belting and an apparatus for making the same, which is illustrated somewhat diagrammatically in the accompanying drawing, wherein—

Figure 1 is a side elevational view of an apparatus for putting a strip of fibrous material under tension in order to stretch the same; Fig. 2 is a plan view of a part of the 40 strip of material shown in elevation in Fig. 1; Fig. 3 is an edge view taken longitudinally of the strip of material of Fig. 2 after the same has been stretched; Fig. 4 is a transverse sectional view thereof taken on 45 the line 4—4 of Fig. 3; Fig. 5 is a longitudinal edge view of the strip of stretched material after having a coat of cement applied to each of the bearing surfaces thereof preparatory to the application of traction surfaces such as sheets of leather; Fig. 6 is a 50 longitudinal view of the edge of the structure after the leather sheets have been applied thereto; and Fig. 7 is an enlarged sectional view of the completed structure, the 55 same being taken on the line 7—7 of Fig. 6.

Referring now more particularly to Fig. 1 of the drawing it will be observed that I have here shown for purposes of illustration an apparatus comprising oppositely disposed 60 frame members 10 (one not shown) at one end of each of which is provided a split journal bearing composed of parts 11—12 for revolvably supporting a shaft 13 on which a drum 14 is mounted, the opposite end of 65 the frame 10 being provided with clamp

members 15—16 which may be secured together in any suitable manner, such as by bolts 17. The drum 14 is cut away as indicated at 18 for the reception of one end 19 of the strip of fabric 20, a clamping member 70 21 secured to the drum 14 by means of bolts 22 serves to secure such end 19 of the strip 20 in position on the drum, another part of the strip being secured by the clamping device, including the members 15, 16 and 17. 75 For the purpose of revolving the drum in the direction indicated by the arrow, and thereby stretching the fabric 20, suitable means such as a crank handle 23 mounted on the shaft 13 may be employed. 80

Referring now more particularly to Figs. 2 to 4, it will be observed that on carrying out the extension of the sheet of fabric 20 by means of suitable apparatus, such as is above indicated, the fabric may be stretched and 85 elongated from its condition illustrated in full lines in Fig. 2 to the position indicated in dotted lines in such figure, which is purely diagrammatic and for the purposes of illustration. The stretching of the fabric just referred to, in case of a piece of textile fabric such as canvas, will serve to straighten the longitudinal or warp threads 24 from their curved condition shown in Fig. 1 to their 90 straight condition shown in Fig. 3, and at 95 the same time however increase the curve in the woof threads, thus not only elongating the fabric, but also narrowing it from its form shown in full lines in Fig. 2 to its form shown in Fig. 4. At this stage of the belt 100 making process I subject the fabric to suitable fixing or setting treatment such as the application of the interstitial filler which is above referred to, and which serves to retain the fabric in stretched condition, and when such filler has dried I apply, when and if desired, to either of the surfaces 26 or 27 or both thereof, suitable coats of cement as indicated at *a* and *b* for the attachment of traction surfaces, such as sheets of leather 110 28 and 29.

On viewing Fig. 7 the parallelism of the several warp threads 24, and likewise the extreme curvature of the woof threads 25 will be clear, and the filling in of the interstices by the use of the filler 30 and the cement above referred to will also be apparent. 115

Having thus described my invention and illustrated its use, what I claim as new and desire to secure by Letters Patent is:

1. A belting comprising a fibrous tension element stretched to a point approaching its limit of elasticity and fixed in such stretched condition, and a traction surface element of relatively less stretched leather secured 125 thereto.
2. A belting comprising a fibrous tension element stretched to a point approaching its limit of elasticity and provided with a filler to retain it in such stretched condition, and 130

a traction surface element of relatively less stretched leather secured thereto.

3. A belting comprising a tensioned fibrous transmission element, means for fixing said element in such stretched position and a relatively less-tensioned traction surface secured thereto.

4. The process of making belting and the like which consists in pre-stretching a fibrous transmission element and fixing or setting it in such stretched condition by a composition of gelatin and isinglass and then applying a traction surface element thereto.

15 5. The process of making belting and the like which consists in pre-stretching a fibrous transmission element, treating it with an interstitial filler to retain it in such stretched condition, and then securing a traction surface of leather thereto.

6. A belting comprising an inner element stretched to a point approaching its limit of elasticity, means for fixing said element in such stretched position and outer elements 25 stretched to a relatively less extent whereby the belt can be readily flexed without exceeding the limit of elasticity of any of its component parts.

7. The process of making belting and the like which consists in stretching the belting and then impregnating the belting with an interstitial filler and then applying a traction surface element to the stretched and filled belting.

30 8. The process of making belting or the like which consists in stretching the belting and then impregnating the belting with an interstitial filler, and then applying a stretched traction surface element to said 35 stretched and filled belting.

9. In belting, a stretched woven fabric having incorporated therein a gelatinous filler for preventing the fabric from return-

ing to its original condition, said filler containing an ingredient for rendering it flexible.

10. A belting comprising a tensioned fibrous element fixed in tensioned condition by a composition of gelatinous material and linseed oil whereby it is restrained from 50 retracting materially toward its initial state and whereby the gelatinous matter is rendered flexible to permit the belting to turn readily over a small pulley.

11. A belting comprising a tensioned fibrous element fixed in tensioned condition by a composition of gelatinous material, adhesive and linseed oil whereby it is restrained from retracting materially toward its initial state and whereby the gelatinous 60 matter is rendered flexible to permit the belting to turn readily over a small pulley.

12. A belting comprising a fibrous transmission element elongated to within 20 per cent. of the elongation required to bring it 65 to its elastic limit, a traction surface element elongated less than 50 per cent. of the elongation required to bring it to its elastic limit attached to said fibrous transmission element, and means for fixing said transmission element in such elongated condition.

13. The process of making belting or the like which consists in pre-stretching a fibrous transmission element, impregnating it with 75 a gelatinous composition to retain it in such stretched condition, drying the treated fibrous element and then cementing a traction surface element thereto.

In testimony whereof I have hereunto 80 signed my name in the presence of the two subscribed witnesses.
